DISPENSING APPARATUS

Clement P. Griffith, Fort Wayne, Ind., assignor to
 S. F. Bowser & Company, Inc., Fort Wayne,
 Ind., a corporation of Indiana

Application August 12, 1929, Serial No. 385,165

39 Claims. (Cl. 221—95)

My invention relates to dispensing apparatus particularly adapted to the dispensing of gasoline at filling stations although it may have a general application, and one of the objects of my invention is the provision of improved apparatus of this type to permit the operator to have complete control at the dispensing nozzle of the entire apparatus.

More particularly it is the object of the invention to provide in dispensing apparatus power-operated mechanism combined with controlling means associated with the dispensing nozzle so that a one-point control at the nozzle may be had for starting and stopping the operation of the dispensing unit and effecting delivery of the liquid from the nozzle.

Another object of the invention is the provision of manually-operated mechanism at the dispensing unit for controlling the starting and stopping of the dispensing apparatus independently of the control mechanism associated with the nozzle.

Another object of the invention is the provision of improved and efficient interlocking mechanism associated with the mechanism for controlling the dispensing apparatus so that when the nozzle is inserted in an opening in the housing of the dispensing unit the dispensing apparatus cannot be operated either by controlling mechanism at the nozzle or by the manually-operated mechanism at the dispensing unit.

Other objects of the invention will appear hereinafter, the novel features and combinations being set forth in the appended claims.

Referring to the accompanying drawings—

Fig. 1 represents a dispensing system embodying my improvements;

Fig. 2 is an enlarged elevational view of the upper portion of the dispensing unit shown in Fig. 1, including the dispensing nozzle and the control mechanism associated therewith;

Fig. 3 is an enlarged elevational view of the lower left-hand portion of Fig. 2 with the interlocking mechanism added;

Fig. 4 is a plan view of the structure shown in Fig. 3;

Fig. 5 is an elevational view of the right-hand side of the construction shown in Fig. 3 with a portion of the air pressure motor shown in elevation;

Fig. 6 is an enlarged sectional elevation of the valve mechanism associated with the nozzle with the controlling means of the air pressure motor shown in elevation;

Fig. 7 is an inverted sectional elevation of the

air pressure controlling valve mechanism associated with the nozzle;

Fig. 8 is an elevational view of the main controlling valve in the dispensing unit, with the interior valve mechanism shown in dotted lines;

Fig. 9 is a sectional elevation of the main valve structure taken on the line 9—9 of Fig. 8;

Fig. 10 is a sectional elevation of the mercury switch for controlling the electric motor connected to a pump in the dispensing system;

Fig. 11 is a sectional elevation taken on the line 11—11 of Fig. 10 looking in the direction of the arrows, with the parts somewhat enlarged as compared with Fig. 10; and

Fig. 12 represents a wiring diagram of the electrical circuits.

Referring to Fig. 1 showing the adaptation of my one-point control system from the dispensing nozzle, 13 designates a storage tank which is adapted to be buried in the ground and filled with gasoline through the fill-pipe 14. By means of a rotary pump 15 operated by an electric motor 16 the gasoline in the tank 13 may be drawn through the suction pipe 17 through the line valve 18 into the gasoline pipe 19. The line valve 18 is a check-valve which opens toward the pipe 19, but prevents flow from the pipe 19 back into the suction pipe 17.

The pump 15 forces gasoline into the vertical pipe 20 and down the pipe 21 after passing through the air release 22. From the pipe 21 the gasoline passes into the horizontal pipe 23 to the manual valve 24.

When the hand-operated valve 24 is open the gasoline may flow through a suitable screen filtering device 25 into a pipe 26 and thence through the main valve 27 into and through a meter 28 from which the gasoline flows upwardly through the vertical pipe 29 to the sight-glass 30 at the upper end of the flexible hose 31. To the free end of the flexible discharge hose is connected the valve-controlled nozzle 32.

The dispensing unit is provided with a dial 33 with pointers 34 and 35 associated therewith and operated by the mechanism of the meter 28. The pointers may be re-set by the knob 36. The housing 37 may have translucent dials on opposite sides thereof with an incandescent lamp and a reflector in the canopy 38 for illuminating the rear sides of the dials. The dials may have "quart" and "gallon" indications thereon and the longer pointer 34 may be for the purpose of representing "quarts" and the shorter pointer 35 for representing "gallons" when in certain numbered positions on the dials. For instance, for a

complete rotation of the pointer 34 the pointer 35 may move forward one step to indicate one gallon.

The dispensing unit shown includes a wet hose in that the nozzle is provided with a valve 39 which is closed when no dispensing operation is taking place and therefore the hose 31 always remains filled with gasoline. It should be understood, however, that my invention is also applicable to dry hose dispensing units, the principal object being to enable the operator to have a one-point control of the dispensing apparatus at the nozzle.

The main dispensing valve 27 is shown in detail in Figs. 8 and 9. The lower end of the valve body 40 is closed by means of a screw-threaded plug 41 which serves as a support at 42 for the spring 43 acting on the valve 44 to hold the same against the valve seat 45. The valve stem 46 is guided into the recess 47 on the upper side of the screw plug 41.

A rod 48 extends freely into a recess 49 in the valve stem 46. The upper end of the rod 48 is pivoted at 50 to the disc 51 which is secured to the inner end of the rock shaft 52. The rock shaft 52 extends through a packing 53 which is provided with a gland 54 pressed against the packing by the spring 55 which is held in place by the screw-threaded cap 56. The packing box 57 is screw-threaded at 58 into the body 40 of the valve structure 27.

The outer end of the rock shaft 52 is threaded at 59 to receive the nut 60 so that the crank 61 may be secured to the rock shaft 52. It will thus be seen that when the crank arm 61 is actuated in a clockwise direction as viewed in Fig. 8, the push rod 48 will be moved downwardly to lower the valve stem 46 in the guideway 47 and thereby open the valve 44 against the action of the spring 43. When the crank arm 61 is released the spring 43 will automatically close the valve 44 and restore the crank arm 61 to its initial position.

By referring to Figs. 3, 8 and 9 it will be seen that the threaded portion 62 of the valve body 40 is connected to the pipe 26 and the screw-threaded portion 63 is connected to the pipe 64 which extends upwardly to the meter 28.

In order to open the valve 27 automatically, I have provided a pneumatic motor 65 which is under the control of the operator at the nozzle 39. As shown in Fig. 5, the pneumatic motor 65 comprises a casting, the lower end of which is closed by the screw-threaded cap 66. Within the interior cylinder 67 is a piston 68 to the lower side of which is connected a plunger 69 movable vertically through the cylindrical guide 70 secured to the cap 66. A spring 71 surrounds the cylindrical guide 70 and the plunger 69 and is located between the top of the cap 66 and the bottom of the piston 68.

The plunger 69 extends through an opening at the center of the cap 66 and its lower end rests upon the horizontal arm 72 which is provided with a collar at its left-hand end, the latter being keyed at 73 to the lower end of the rod 74. The rod 74 is guided through openings in the brackets 75 and 76 which are secured to the inner wall of the housing 77 which encloses the main dispensing valve 27 and the operating mechanism therefor. The upper end of the rod 74 is connected by a pin and slot as indicated at 78 in Fig. 3, to the crank arm 61. Therefore when the pneumatic motor is operated to depress the piston 68 against the action of the spring 71, the

plunger 69 will actuate the bracket arm 72 and push down the rod 74 through the guides 75 and 76 and thereby turn the crank arm 61 in an anti-clockwise direction as viewed in Fig. 3, to effect the opening of the valve 44 shown in Fig. 9. When air pressure on the piston 68 is relieved the spring 71 restores the plunger 69 to its initial position and the spring 43 simultaneously restores the rod 74 and the arm 72 to their initial positions and re-closes the valve 44. In order to permit free downward movement of the piston 68 an air port is provided at 79 in the cap 66 as shown in Fig. 5.

Air pressure may be conducted into the cylinder 67 through the connection at 80 as shown in Figs. 2 and 5. A small flexible pipe 81, preferably of metal such as copper, is led upwardly from the connection 80 as shown in Fig. 2, to the conduit 82 which is mounted by means of the brackets 83, 83 on the vertical pipe 29. Also extending upwardly into the conduit 82 is a compressed air pipe 84, preferably of flexible metal such as copper. By referring to Fig. 1 it will be seen that the pipe 84 is connected to a compressed air supply pipe 85.

By means of a suitable air tube adapter 90, 90' as shown in Fig. 2, the upper ends of the two metal pipes 81 and 84 are connected to the passageways 81' and 84' in the flexible hose 87 mounted on and attached to the delivery hose 31 so as to move bodily therewith. For this purpose the flexible hose 87 may be secured to the delivery hose 31 by spirally wound tape, or by means of clamps 88.

Air valve controlling mechanism 89 is connected by means of an air tube adapter 90, 90' to the flexible pipe 87 having the two passageways 81' and 84' therethrough. The air valve mechanism 89 may be secured at 91 to the bracket 92 on the nozzle housing 93 as shown in Fig. 6.

The details of the valve mechanism 89 are shown in Fig. 7. In this view the air tube adapter is shown diagrammatically at 90' in the form of two branches of the flexible hose 87 having the passageways 81' and 84' leading respectively to the ports 95 and 94. These ports may be in the form of nipples 93 and 97 screw-threaded into the body portion of the valve mechanism 89. The port 95 communicates with the passageway 97 and leads to oppositely disposed valve ports 98 and 99. The passageway 97 may be closed at 100 by means of a screw plug.

A valve stem 101 has mounted thereon two valves 102 and 103. Between the nipple 96 and the valve 102 is a spring 104 which urges the valve 102 to closed position. The valves 102 and 103 are so related that when the port 98 is closed the port 99 is open. When the valve 103 closes the port 99 the valve 102 opens the port 98. When the valve 102 is closed, communication from the source of compressed air through the pipe 84 to the pneumatic motor 65 is cut off. When the valve 102 is closed the valve 103 is open and at this time the pneumatic motor 65 is connected through the pipe 81 to the passageway 81' and thence through the passageway 97 and the port 99 to the chamber 105 and the exhaust port 106, thereby relieving the air pressure on top of the piston 68 and permitting the spring 71 to return the piston to its initial position shown in Fig. 5.

As shown in Fig. 7, a plunger 107 extends through a bearing 108 which is screw-threaded into one end of the cylinder 109. At the inner end of the plunger 107 is a piston 110 movable along the cylinder 109. The inner end of the plunger 75

107 is provided with a recess 111 fitting over the valve stem 101. The piston 110 presses against the spring 112 when the plunger 107 is moved inwardly. The inward movement of the plunger 107 causes the piston 110 to act as a valve to cut off the exhaust port 106 from the chamber 105 and the port 99. This is followed by the closure of the valve 103 and the opening of the valve 102 when sufficient force is exerted on the spring 112 to counteract the spring 104. It is desirable to close the port 108 before the valve 102 is opened so that compressed air cannot escape from the supply passageway 84 through the exhaust port during the interval when the valves 103 and 102 are both open.

By referring to Fig. 6 it will be seen that a valve operating lever 113 is pivoted to the nozzle at 114 in such a manner that the boss 115 will engage the valve stem 116 to open the nozzle valve 117 against the action of the spring 118. Secured to the valve 117 is a metal cup 19 which is provided with openings at 120 so that the closing of the valve 117 will not be too abrupt. The valve stem 116 extends through packing 121 in a packing box 122. When the nozzle is grasped in the operator's hand with his palm over the valve 117, his fingers may be used to move the lever 113 to the dotted line position illustrated at 113' and this operation will open the valve 117, 120. Before the valve 117, 120 is opened, however, the cylindrical end 123 of the lever 113 rides along the cam face 124 of the lever 125 which is pivoted at 126 to the nozzle housing 93. A boss 127 on the lever 125 is in position to engage the plunger 107 to effect sufficient movement of the piston 110 to close the exhaust port 106, close the valve 103 and open the valve 102 before the valve 117, 120 is opened. To assure this sequence of movements of the valves the cylinder 119 is provided with the ports located at 120. When the lever 113 is moved to its dotted line position 113' the cylindrical end 123 rides on the cam face 128, thereby making it easier for the operator to hold the lever in its dotted line position 113'. A lever guard 129 is connected to the valve housing 93 as shown in Fig. 6, and may be provided with a cross-plate 130 to serve as a sliding bearing for the ends of the levers 113 and 125. A guard plate 131 for the valve mechanism 89 may also be provided. A hook 132 may be made integral with the guard 129 so that the nozzle may be hung on the operating lever 133 as illustrated in Fig. 1. The nozzle may be provided with a flexible extension 134 as shown in Fig. 2, which flexible extension may be inserted through the opening 135 if desired for hanging the nozzle on the lever 133.

In Fig. 6 I have shown a non-draining valve 136 provided with a valve stem 137 extending through a guide opening 138 in the bracket 139 on the interior of the housing 93. A spring 140 is of sufficient strength to close the valve 136 when no pump supply pressure is being exerted in the delivery hose 31. The spring 140 is sufficient to counteract the head of liquid in the pipe 31 when the pump supply pressure is discontinued and therefore the hose will be kept full of liquid when the pump supply pressure is cut off.

As shown in Figs. 3 and 5, an extension 141 is carried by the bracket arm 72 and to this extension 141 is pivoted at 142 a bar 143 which has a sliding connection through a diametrical opening in the shaft 144 as shown in Figs. 4 and 10. The shaft 144 is mounted in the bearing 145 of the switch-box 146. Mounted on the inner end of the shaft 144 are spring clips 147 for engaging the

opposite tapered surfaces of the vacuum tube 148, preferably of glass, and containing within the same a quantity of mercury 149 for engaging the terminals 150 and 151 which project into the glass vacuum tube 148 as diagrammatically illustrated in Fig. 12.

The supply mains 152 from the source of electrical supply are connected to the electric motor 15 and through fuses 153 by means of the leads 154 and 155 to the terminals 151 and 150 respectively. The leads 154 and 155 may be connected to metal plates 156 and 157 on the block of insulation 158 mounted on the inside of the switch-box 146 as shown in Figs. 10 and 11. This will permit the use of slack looped leads 154' and 155' to afford ample freedom of movement of the mercury tube 148 when tilted by rocking the shaft 144. In the wiring diagram of Fig. 12 I have also shown an incandescent lamp 159 connected through fuses 160 to the supply mains 161, this incandescent lamp 159 being located in the reflector housing 38 to illuminate the inside surfaces of the translucent or transparent dial faces 33.

It should be understood that when the operating lever 113 is moved to its dotted line position shown in Fig. 6 the exhaust port 106 of Fig. 7 will first be closed and this will be followed by the closing of the valve 103 and the opening of the valve 102. Air pressure supply will then pass through the pipe 85 as shown in Fig. 1 into the pipe 84 and thence through the passageway 84' of the flexible hose 87. This air pressure supply will then pass through the port 98 and passageway 97 into the passageway 81' and the pipe 81 to the top of the cylinder 87 shown in Fig. 5. The piston 68 will move downwardly against the action of the spring 71 while the air below the piston 68 will be exhausted through the port 79. This will cause the plunger 68 to be moved downwardly to pull the rod 74 downwardly, thereby operating the crank 61 in an anticlockwise direction as viewed in Fig. 3 and in a clockwise direction as viewed in Fig. 8. This will cause the main dispensing valve to open to afford communication between the supply pipe 23 and the pipe 26 to the pipe 64 and thence to the delivery hose 31. At the same time that the dispensing valve 27 is opened the mercury switch will be tilted to a horizontal position from its inclined position in Fig. 12. The mercury in the closed vacuum tube 148 will thereupon connect the terminals 150 and 151 to start the motor 15 and to continue to operate it so long as the terminals 150 and 151 are connected by the mercury 149.

When the motor 15 is operated the hydraulic pump 16 will be operated to pump gasoline through the suction pipe 19 and supply it to the pipe 20 through the air release 22 and the pipe 21 and thence through the pipe 23, the pipe 26, main valve 27 and the other connections above described, to the delivery hose 31.

It is intended that the operator shall move the operating lever 113 by a continuous swing thereof to its dotted line position and that the mercury switch shall be set to effect the starting of the electric motor and the pump substantially at the same time that the main valve 27 is opened so that by the time that the nozzle valve ports 120 are opened sufficient supply pressure from the pump will be exerted in the delivery hose 31 to open the drain valve 136 and effect flow of gasoline through the nozzle to the car. If, however, it should happen that the ports 120 are not sufficiently uncovered when the motor and pump are operating, the by-pass 162 will afford relief by 75

reason of the check-valve 163 shown in Fig. 1. It will also be seen by referring to Fig. 1 that a vent pipe 164 is connected to the atmosphere at 165 and to the top of the supply reservoir 13 5 and to the top of the air release 22.

When the operator releases the lever 113 the spring 118 closes the valve 117, 120 and returns the lever 113 to its initial position. At the same time the plunger 107 is returned to its initial 10 position by the springs 104 and 112 shown in Fig. 7. The lever 125 will thus be returned to its full line position shown in Fig. 6.

When the operator releases the lever 113 and therefore also the lever 125 the spring 104 is 15 free to act to close the valve 102 shown in Fig. 7. This will also effect the opening of the valve 103 and the spring 112 in turn acts on the piston 110 to uncover the exhaust port 106 so that the chamber 105 will be connected to the atmosphere.

20 This will result in the cylinder 67 of Fig. 5 being connected to atmosphere above the piston 68 through the pipe 81, passageway 81', passageway 97 and port 99, chamber 105 to exhaust port 106. The spring 43 shown in Figs. 8 and 9 will then 25 close the valve 44 and act through the rock shaft 52 and the crank 61 to lift the rod 74 back to its initial position. This will also lift the extension 141 to its initial position and swing the rod 143 to its position shown in Fig. 3. Thereupon the 30 mercury switch will be tilted to the position shown in Figs. 3 and 12, thereby disconnecting the terminals 150 and 151 and cutting off the electrical current supply to the motor 15, causing the pump 16 to stop.

35 If for any reason the air pressure supply for the air motor 67 should fail, the main valve 27 may be opened by the lever 133 which is pivoted at 166 to the bracket 167 on the housing 77 as shown in Fig. 2. The inner end of the lever 133 is provided 40 with an arm 168 which is adapted to swing down on top of the nut 60 shown in Fig. 9 so as to swing the crank 61 to open the valve 44. When this occurs the rod 74 will also be moved downwardly to effect the operation of the mercury switch to its 45 closed position. Therefore by moving the lever 133 upwardly manually, the main valve 27 may be opened and the electric switch closed to start the motor 15 and the pump 16.

Locking mechanism to prevent the operation of 50 the main valve 27 and the electric controlling switch may be provided for operation by inserting the nozzle through the opening 169 in the housing 77. By referring to Figs. 3 and 5 it will be seen that a plate 170 is mounted on the interior 55 of the housing 77 back of the opening 169. The upper end of the plate 170 is secured to a shaft 171 mounted in a bearing 172 on a bracket 173 secured to the inner side of the housing 77. A bearing for the shaft 171 may be also located 60 at 174. A quadrant arm 175 is carried by one end of the shaft 171 in such a position that when the plate 170 is swung inwardly by insertion of the nozzle through the opening 169 in the housing, the quadrant arm 175 will be swung into position 65 below the arm 176. The arm 176 is secured rigidly to the upper end of the rod 74. Therefore when the quadrant 175 is moved below the arm 176 such quadrant will act as an abutment against downward movement of the rod 74. Consequently 70 when the nozzle is inserted through the opening 169 into the housing neither the main valve 27 can be opened, nor the mercury switch closed.

It should be particularly noted that by means 75 of the single lever 113 at the nozzle a one-point control by a single person may be had at the nozzle.

zle. It will also be apparent that by reason of the foregoing construction, the one point control is a complete control in that the movement of the nozzle valve 117 toward and away from its seat may be adjustably varied by movement of the 5 nozzle valve lever 113 to regulate the flow of liquid through the nozzle, without changing the condition of the control switch. The response to the operation of the valve mechanism is very quick because the supply of air pressure is extended at 10 all times through the passageway 84' up to the valve 102 at the nozzle. As soon as the valve 102 is opened and the valve 103 closed, sufficient air pressure is exerted very quickly in the pneumatic motor 67 to effect the opening of the main dispensing valve 27 and the closure of the mercury vacuum switch. A wet hose system is shown in that the valve 136 keeps the supply hose 31 filled with liquid even when the pump is not operating. The intervals in the sequence of operations are 20 so short as to cause the gasoline to flow through the nozzle to the car almost immediately after the operating lever 113 has been moved to its dotted line position and the nozzle valve 117, 120 opened. 25

Obviously those skilled in the art may make various changes in the details and arrangement of parts without departing from the spirit and scope of the invention as defined by the claims hereto appended and I wish therefore not to be 30 restricted to the precise construction herein disclosed.

Having thus fully disclosed an embodiment of my invention, what I desire to secure by Letters Patent of the United States is: 35

1. In dispensing apparatus, the combination with dispensing mechanism comprising a delivery hose and a discharge nozzle, of a check-valve connected to said hose and opening toward said nozzle when operating pressure is exerted on said 40 valve but closing automatically when such pressure is withdrawn to prevent draining of the hose, means associated with said nozzle for controlling the operating pressure, a self-closing valve at the nozzle for controlling flow therethrough, and a 45 manually actuated lever on the nozzle for both operating said controlling means and opening said valve.

2. In dispensing apparatus, the combination with dispensing mechanism comprising a main 50 valve, a hose and a discharge nozzle, of a pump for supplying liquid to said dispensing mechanism, an electric motor for operating said pump, a mercury switch for controlling said motor, a pneumatic motor for opening said main valve and closing said switch to start and operate said motor and pump, and air valve mechanism at the nozzle to control said pneumatic motor.

3. In dispensing apparatus, the combination with a dispensing unit comprising a housing, a delivery hose, a discharge nozzle, a self-closing main valve in the housing, an electric motor control switch in the housing, a self-closing valve at the nozzle, and a lever for opening the last-named nozzle, of a pump for supplying liquid to said hose through said main valve, an electric motor for operating said pump, a manual lever for opening said main valve and closing said switch, and interlocking mechanism operable by inserting said nozzle through an opening in said housing for preventing operation of said manual lever to open said main valve or close said switch. 60 65 70

4. In dispensing apparatus, the combination with a dispensing unit comprising a housing, a delivery hose, a discharge nozzle, a self-closing 75

valve for the nozzle, a self-closing main valve in the housing, a mercury electric switch in the housing, a pneumatic motor in the housing for opening the main valve and closing said switch, air valve mechanism at the nozzle for controlling said pneumatic motor, of a pump for supplying liquid to said hose through said main valve, an electric motor under the control of said switch for operating said pump, and a lever at the nozzle connected to said air valve mechanism and to the nozzle valve to first operate said air valve mechanism to secure the operation of said pneumatic motor, the opening of said main valve, the closing of said switch and the operation of said pump before the nozzle valve is opened by said lever.

5. In dispensing apparatus, the combination with dispensing mechanism comprising a flexible hose and a delivery nozzle at the free end thereof, of operating means for said dispensing mechanism comprising a fluid pressure motor, valve mechanism associated with said nozzle for controlling said fluid pressure motor, a self-closing valve at the nozzle, and a grip actuating device connected to said valve mechanism and to said self-closing valve to operate on pressure thereof to open said self-closing valve and operate said valve mechanism.

6. In dispensing mechanism, the combination with dispensing mechanism comprising a delivery hose and a discharge nozzle at the free end thereof, of a flow meter in the supply line of the dispensing mechanism for registering the liquid discharged from said hose through said nozzle, a self-closing valve at the nozzle for controlling the flow from said hose through said nozzle, means for operating the dispensing mechanism and producing pressure in said hose, valve mechanism at the nozzle for controlling said operating means, and means at the nozzle for opening said self-closing valve and operating said valve mechanism to effect flow of liquid from said hose through said nozzle while said meter registers the quantity of liquid discharged from said nozzle.

7. In dispensing apparatus, the combination with dispensing mechanism comprising a delivery hose and a discharge nozzle, of a valve at said nozzle for controlling the flow of liquid from said hose through said nozzle, means comprising a fluid pressure motor for operating said dispensing mechanism, valve mechanism mounted on said nozzle for controlling said fluid pressure motor, and mechanism on the nozzle for operating said valve and said valve mechanism simultaneously to secure operation of the dispensing mechanism and flow of liquid through said nozzle immediately upon actuating said operating mechanism at the nozzle.

8. In a nozzle for dispensing apparatus, the combination with a nozzle housing, of a self-closing valve therein, air valve mechanism mounted on said housing, a lever pivoted to said housing in position to open said self-closing valve, and an auxiliary lever pivoted to said housing in position to be engaged by the free end of said first-named lever to effect the operation of said air valve mechanism when said first-named lever is actuated to open said self-closing valve.

9. In a nozzle for dispensing apparatus, the combination with a nozzle housing, of a valve for the nozzle, a lever pivoted to said housing in position to operate said valve, and means co-acting with said lever for assisting the operator in holding said lever pressed toward valve opening position.

75 10. In a nozzle for dispensing apparatus, the

combination with a nozzle housing, of a valve mounted in said housing, a lever for opening said valve, and a cam-faced spring-pressed lever for engaging the free end of said first-named lever to assist the operator in holding the valve in open position.

5 11. In a nozzle for dispensing apparatus, the combination with a nozzle housing, of a spring-pressed self-closing valve therein having a spindle projecting outwardly therefrom, a lever pivoted to said housing in position to engage said spindle to open said valve against the action of said spring, an auxiliary lever having a cam-face engaged by the free end of said first-named lever, and spring-pressed mechanism engaging said auxiliary lever to hold the same against the free end of said first-named lever when the latter is in its position for opening said valve.

10 12. In a nozzle for dispensing apparatus, the combination with a nozzle housing, of a self-closing valve therein comprising a stem projecting therefrom, an operating lever pivoted to said housing in position to engage said stem, an auxiliary lever pivoted to said housing and having cam faces engaged by the free end of said first-named lever, and spring-pressed valve mechanism operated by said auxiliary lever when the free end of said first-named lever moves along said cam faces.

20 13. In dispensing apparatus, the combination with dispensing mechanism comprising a delivery hose and a discharge nozzle, of a pump for supplying liquid to said hose, an electric motor for operating said pump, an electric switch hermetically sealed from the atmosphere and connected to said motor to control the operation thereof, and means controlled from the nozzle for operating said switch.

25 14. In dispensing apparatus, the combination with a dispensing unit comprising a housing with a main valve therein, a delivery hose, a discharge nozzle, and an electric switch, of a pump for supplying gasoline to said dispensing unit, an electric motor for operating said pump under the control of said switch, a motor for operating said main valve and closing said switch, means at the nozzle for controlling said last-named motor, a device in position to be actuated by said nozzle when inserted through an opening in said housing, and interlocking mechanism operated by said device when said nozzle is inserted through said opening to prevent the opening of said main valve and the closing of said switch.

30 15. In dispensing apparatus, the combination with a dispensing unit comprising a housing, a delivery hose, a discharge nozzle, a main valve in the housing, a switch in the housing, a valve at the nozzle, and means at the nozzle for controlling one of said valves, of a pump for supplying liquid to said hose through said main valve, an electric motor for operating said pump, a motor for operating said main valve and closing said switch, means at the nozzle for controlling said last-named motor, an actuating device in said housing at an opening therein adapted to receive said nozzle, and mechanism connected to said actuating device for preventing opening of said main valve and closing of said switch when said nozzle is projected through said opening into said housing.

35 16. In dispensing apparatus, the combination with a dispensing unit comprising a housing, a delivery hose, a discharge nozzle, a main valve, and a mercury electric switch, of a pneumatic motor within said housing for operating said

- main valve and said switch, mechanism at the nozzle for controlling said pneumatic motor, a self-closing valve for the discharge nozzle, and means comprising a single lever for operating said controlling mechanism and opening said valve to secure flow through said hose and said nozzle on the opening of said main valve and the closing of said switch.
17. In a nozzle for dispensing apparatus, a combination with a nozzle housing, of a self-closing valve, a lever for opening said valve, controlling air valve mechanism on said housing, an additional lever on said housing to operate said air valve mechanism, and means for supporting said levers on said housing in position to cause the first-named lever to engage the second-named lever and operate said air valve mechanism in a predetermined sequence relative to said self-closing valve.
18. In dispensing apparatus the combination with dispensing mechanism including a delivery hose, with a delivery nozzle at the free end thereof, of power actuated apparatus for operating said dispensing mechanism, a valve at the nozzle for controlling the flow of liquid through said hose and said nozzle, a pivoted lever for operating said valve to effect the opening and closing thereof, air valve mechanism at the nozzle for controlling said power actuated apparatus, and an auxiliary lever operated by said first-named lever to effect the operation of said air valve mechanism.
19. A dispensing apparatus, the combination with a dispensing mechanism comprising a delivery nozzle, of means for operating said dispensing mechanism, mechanism associated with the nozzle for controlling said operating means, and means comprising inter-engaging levers to enable a single operator to effect the starting and stopping of said operating means and the starting and stopping of the flow of liquid from said nozzle.
20. In a dispensing apparatus, the combination with a dispensing mechanism comprising a flexible hose with a delivery nozzle at the free end thereof, of means for operating said dispensing mechanism, a valve at the nozzle for controlling the flow of liquid therefrom, valve mechanism associated at the nozzle for controlling said operating mechanism, and means comprising inter-engaging levers for opening said valve and operating said controlling means to effect operations of said operating mechanism and the delivery of liquid from said nozzle by a one point control at the nozzle.
21. In dispensing apparatus, the combination with dispensing mechanism comprising a delivery nozzle, of means for operating said dispensing mechanism, a valve at the nozzle for controlling the flow of liquid therefrom, means associated with nozzle for controlling said operating means, two levers pivoted to said nozzle, one for opening said valve and the other for operating said controlling means, a cam mechanism between said levers for enabling the valve nozzle lever to operate the other lever.
22. In dispensing apparatus, the combination with dispensing mechanism comprising a delivery hose and a discharge nozzle, with a self-closing valve at said nozzle, means mounted directly on said nozzle for controlling the operations of said dispensing mechanism, and means comprising a pressure lever connected to said valve and also to said controlling means at said nozzle to effect the opening of said valve and the operation of said controlling means by pressure exerted on said lever.
23. In dispensing apparatus, the combination with a dispensing unit, of a liquid supply line, means for furnishing an unlimited continuous supply of liquid under pressure to said supply line, a delivery hose at one end of said supply line, a flow meter in the supply line for continuously metering any amounts of liquid discharged from said hose, means in the dispensing unit for effecting flow control of liquid under pressure through said supply line, a nozzle at the delivery end of said hose, a controlling valve at the nozzle, a device on the valve itself for effecting the operation of said flow controlling means, a conduit connecting said device on the nozzle to said flow controlling means, and a single lever for both operating the nozzle valve and said device.
24. In dispensing apparatus, the combination with dispensing mechanism comprising a delivery hose and a discharge nozzle, of a quantity flow indicator operable by liquid flowing in the supply line, a valve at the nozzle for controlling the discharge of liquid from said hose through said nozzle, a control device on the nozzle, single throw lever mechanism for operating both said valve and said control device, and means comprising a flexible conductor extending along the hose but immovable relatively thereto for connecting said control device to the operating parts of the dispensing mechanism.
25. In dispensing apparatus, the combination with dispensing mechanism comprising a delivery hose and a discharge nozzle, of a self-closing valve at the nozzle, a meter in the supply line, a quantity indicator operated by said meter upon flow of liquid through said supply line and from the nozzle while said valve is open, mechanism for automatically operating said dispensing mechanism, means at the nozzle for controlling said operating mechanism, a flexible conductor extending along the hose but immovable relative thereto to connect said controlling means at the nozzle to said automatic operating mechanism, and a single lever at the nozzle for opening said valve at the nozzle and operating said controlling means at the nozzle to secure immediately upon the opening of the valve at the nozzle flow of liquid therefrom as well as the operation of said quantity indicator and to secure discontinuance of said quantity indicator immediately upon the closing of said valve to cut off the flow of liquid from said hose and the stopping of said operating means.
26. In dispensing apparatus, the combination with a supply line, of a main valve in the supply line, a delivery hose connected to the supply line, means for opening said valve and effecting fluid pressure in the supply line, a delivery hose connected to said supply line, a nozzle at the free end of said hose, a controlling device on the nozzle, a conduit connecting said device to the aforesaid means, a self-closing valve at the nozzle, and single throw lever mechanism on the nozzle for operating said controlling device and said valve.
27. In dispensing apparatus, the combination with dispensing mechanism comprising a delivery hose and a discharge nozzle, of a pneumatic conduit extending along said hose and fixed thereto so as to be relatively immovable, a valve controlling device on the nozzle, a discharge valve at the nozzle, a single throw lever mechanism for operating both the said valve controlling device and said discharge valve, and means at that end of said conduit remote from said nozzle for operating the dispensing mechanism under the

control of said valve controlling device at the nozzle.

28. In dispensing apparatus, the combination with dispensing mechanism comprising a delivery hose and a discharge nozzle, of a pump for supplying liquid to said hose, an electric motor for operating said pump, an electric switch hermetically sealed from the atmosphere and connected to said motor to control the operation thereof, a pneumatic motor for operating said switch, a pneumatic conduit extending along the hose from said nozzle to said motor, valve mechanism on the nozzle for controlling said motor, a valve for controlling flow from the nozzle, a lever for operating said valve, and auxiliary lever mechanism connected to said lever for operation thereby to operate said valve mechanism.

29. In dispensing apparatus, the combination with a dispensing unit comprising a housing, a delivery hose and a discharge nozzle, of a pump for the dispensing unit, an electric motor for operating said pump, an electric switch mounted in said housing and hermetically sealed from the atmosphere, connections between said switch and said motor, a pneumatic motor for operating said switch to control said motor, controlling valve mechanism on the nozzle, a discharge valve at the nozzle, a lever for operating said valve, and connections between said lever and said controlling valve mechanism to enable a single operation of said lever to open the discharge valve and at the same time operate said controlling valve mechanism.

30. In a liquid dispensing system, a liquid delivery line terminating in a flexible hose, controllable means for supplying liquid through said line and hose, a nozzle valve controlling discharge from the hose, and operating means for starting the liquid supplying means and opening the nozzle valve after said means has been started and for closing said nozzle valve and stopping said means after the nozzle valve has been closed.

31. In liquid dispensing systems, a delivery line, a delivery controlling valve in said delivery line, an electric control switch and operating means for closing the switch and opening the delivery controlling valve after the switch is closed and for opening the switch after the delivery controlling valve is closed.

32. In apparatus of the character disclosed, the combination of a liquid dispensing hose, electrically operated means for governing flow of liquid to the hose, a switch for controlling said means, a valve controlling delivery of liquid by the hose and operating mechanism for said switch and valve, including means for introducing a timed relation to throw the switch before opening the delivery valve.

33. In a liquid dispensing system, a liquid delivery line terminating in a flexible hose, controllable means for supplying liquid through said line and hose, a valve controlling discharge through the hose, and operating means for starting the liquid supplying means and opening the valve after said means has been started, and for closing said valve and stopping said means after the valve has been closed.

34. In a liquid dispensing apparatus, the combination with measuring apparatus, a pump, a motor and a delivery hose, of a power-control organ for the motor, a master valve controlling the supply of liquid from the pump to the measuring apparatus, a discharge valve, a manipulating device at the end of the hose, and means

operable by said manipulating device for opening said discharge valve, for placing said power-control organ in the power-on condition, for moving said master valve to the dispensing condition, and for adjusting said discharge valve to regulate the outflow of liquid without changing the condition of said power-control organ.

35. In a liquid dispensing apparatus, the combination with measuring apparatus, a pump, a motor and a delivery hose, of a power-control organ for the motor, a master valve controlling the supply of liquid from the pump to the measuring apparatus, a discharge valve, a manipulating device at the end of the hose, and means operable by said manipulating device for opening said discharge valve, for placing said power-control organ in the power-on condition, for moving said master valve to the dispensing condition, and for adjusting said discharge valve to regulate the out-flow of liquid without changing the condition of said power-control organ or of said master valve.

36. A gasoline dispensing mechanism comprising a pump, control means for the pump, a dispensing line, a nozzle assembly at the delivery end of said dispensing line, a nozzle valve in the nozzle assembly, an operating member in the nozzle assembly for the nozzle valve, a second operating member in the nozzle assembly, means operatively connecting said second operating member and the pump control means, each of said operating members being movable independently of the other for at least a portion of its range of operating movement.

37. A gasoline dispensing mechanism comprising a pump, control means for the pump, a dispensing line, a nozzle assembly at the delivery end of said dispensing line, a nozzle valve in the nozzle assembly, an operating member in the nozzle assembly for the nozzle valve, a second operating member in the nozzle assembly, means operatively connecting said second operating member and the pump control means, each of said operating members being movable for at least a portion of its range of operating movement independently of the other, and manually operable means for operating said members, said manually operable means on actuation being operable to move said valve operating member a predetermined distance before operation of said second operating member.

38. A gasoline dispensing mechanism comprising a pump, control means for the pump, a dispensing line, a nozzle assembly at the delivery end of said dispensing line, a nozzle valve in the nozzle assembly, a guard for said nozzle, an operating member in the nozzle assembly for the nozzle valve and disposed in the plane of the guard, a second operating member in the nozzle assembly and disposed in the plane of the guard, means operatively connecting said second operating member and the pump control means.

39. In a liquid dispensing device the combination of a dispensing pump having an actuatable member, means forming a liquid flow line terminating in a nozzle provided with a displaceable nozzle valve, a plurality of shiftable levers, means actuated by said levers for actuating the nozzle valve and for actuating the pump, said nozzle having a guard lying in the plane of movement of said levers and adapted to protect them from inadvertent operation.
